Inventor:

E. M. Wolff

UNITED STATES PATENT OFFICE.

ELZY M. WOLFF, OF MANSFIELD, OHIO.

DESIGN FOR A MONUMENT.

No. 37,658.

Specification for Design.

Patented Nov. 7, 1905.

Application filed September 18, 1905. Serial No. 279,053. Term of patent 3½ years.

To all whom it may concern:

Be it known that I, ELZY M. WOLFF, a citizen of the United States, residing at Mansfield, in the county of Richland, State of Ohio, have invented a new, original, and ornamental Design for Monuments, of which the following is a specification, reference being had to the accompanying drawing, forming part thereof.

The figure is a front elevation of a monument, showing my new design.

I claim—

The ornamental design for a monument, as shown.

ELZY M. WOLFF.
